UNITED STATES PATENT OFFICE.

HARRY REICHMAN AND ARTHUR R. SPANGENBERG, OF CINCINNATI, OHIO.

COMBINED PACKAGE AND TRASH RECEPTACLE.

1,327,778.

Specification of Letters Patent. Patented Jan. 13, 1920.

Application filed July 15, 1918. Serial No. 244,912.

To all whom it may concern:

Be it known that we, HARRY REICHMAN and ARTHUR R. SPANGENBERG, citizens of the United States, residing in Cincinnati, in 5 the county of Hamilton and State of Ohio, have invented new and useful Improvements in Combined Package and Trash Receptacles, of which the following is a specification.

10 An object of our invention is to produce a receptacle which is provided with separate compartments for the reception of packages and trash and the outer walls of which are rendered additionally useful as a surface 15 upon which to display advertisements.

This object is attained in the receptacle described in the following specification.

In the drawings illustrating an embodiment of our invention:—

20 Figure 1 is a perspective view of a receptacle embodying our invention.

Fig. 2 is an end elevation of our invention as illustrated in Fig. 1.

25 Fig. 3 is a view similar to Fig. 2 but with the door to the trash receptacle opened.

Fig. 4 is a side elevation of our improved receptacle, the door to the package receptacle being of modified form and shown partially opened.

30 Fig. 5 is a transverse sectional view taken on the line 5—5 of Fig. 2.

Fig. 6 is a fragmental perspective view of a corner of our improved construction.

35 Fig. 7 is a fragmental perspective view of a corner plate of our improved construction illustrating a detail thereof.

Fig. 8 is a composite view of a detail of our invention.

40 Fig. 9 is a composite view of a modified form of the detail of our invention illustrated in Fig. 8.

Our improved receptacle is particularly designed to be used at street corners in place of the usual waste paper and trash cans to be found in cities, the particular purpose 45 being to render the appearance of such receptacles more ornamental and at the same time utilize the appearance for a utilitarian purpose, while simultaneously attracting attention to the receptacle and the purpose 50 for which it is placed in position.

The construction consists of a frame 10 comprising the body of the receptacle and having the lower part provided with a com-

partment 11 in which a trash receptacle 12 55 is located removably.

In the upper portion of the body a somewhat smaller compartment is formed in which a receptacle 13 is located removably.

The construction provides for corner posts 60 14 which are continued below the body and are split to provide feet 15, as shown in Fig. 6.

A bottom 16 is formed of angle irons for supporting the receptacle. At its top the 65 frame is provided with angle irons 17 which afford support for the package receptacle 13. A door 18 which is preferably of the sliding type, is provided for affording access to the trash container compartment. In 70 Figs. 1 and 2 we have shown a door 19 for permitting access to the package compartment, the door being hinged at its lower edge and provided with a hasp 20 at its upper edge for locking the door against opening.

This is shown in somewhat modified form in Fig. 4 in which the entire top 21 is hinged and adapted to be lifted to permit 75 the package container to be removed. To permit packages to be dropped into the package 80 container we have provided a slot 22 in each side wall as shown in Figs. 1 and 4. Openings 23 in the sides of the body and openings 24 in the ends thereof, are provided 85 for permitting waste paper and trash to be dropped in the container 12. Suitable signs and reading matter giving directions to the uses of the respective slots, are provided as shown in Figs. 1 and 2.

A feature of our invention is the provision of corner plates 25 which are located within and secured to the corner angle irons of the frame by rivets or other suitable means. Each corner plate 90 is provided with offset edges which are formed with corrugations 26 having channels 27 therein. Back of the plates the plain sheet metal sides 28 and the ends 29 of the body are located. The channels 27 are provided for the reception of springs 30 extending from the ends of metal 100 strips 31 which extend between the corner angle irons of the body and which are located in the offset edges of the plates 25 with the springs located in the channels 27.

Each of these metal strips 31 is provided 105 with a pressed portion 32 the upper edges of which form shelves for supporting advertising cards which may be located between

adjacent strips. The springs 30 may be located in any one of the channels 27 to adjust the positions of the strips according to the width of card to be displayed between 5 adjacent strips. The modified form of strip disclosed in Fig. 9 is provided with integrally formed spring ends 33, lugs 34 being stamped from the strips to provide recesses into which the upper and lower edges of the 10 cards may be slipped.

In placing our improved receptacle for access by those passing along the street, the side of the receptacle shown in Fig. 1, is placed to face the approaching pedestrians, 15 the opposite side bearing the same reading matter and being provided with a like slot so that those approaching from the opposite side will likewise have the uses and purposes of the receptacle brought to their attention. 20 The openings 23 and 24 may be provided on each side and end so that trash may be thrown into the trash receptacle 12 from the street as well as from the sidewalk.

We have found a receptacle of this description to be particularly useful in the collection of magazines, tobacco and other articles 25 for the soldiers and a further adaptation thereof may be the placing of a mail box in the upper portion, thus rendering the con-

struction equally as serviceable as when used 30 for the specific purpose disclosed in the drawing.

Having thus described our invention what we claim is:—

A combined trash and package receptacle 35 having its outer walls adapted to the display of advertising matter thereon, said walls having edge plates spaced therefrom and containing grooves facing the outer surfaces of the walls, strips extending from one edge 40 plate across the adjacent wall surface to the coöperating edge plate and reciprocally mounted in the spaces between the plates and their coöperating wall surface, and springs on the strips adapted to occupy the 45 grooves of the plates to retain the strips in adjusted positions on advertising cards located on the wall surface.

In witness whereof, we affix our signatures in the presence of witnesses.

HARRY REICHMAN.
ARTHUR R. SPANGENBERG.
